CLAIM

The ornamental design for a cocktail stirrer/cocktail maraca, as shown and described.

DESCRIPTION

FIG. 1 is a pictorial view of a cocktail stirrer/cocktail maraca according to the new design, the view being taken from an aspect to one side and below the embodiment; and, FIG. 2 is a pictorial view of the design, taken from an aspect to one side and above.

The aspects of the design opposite those shown in the drawings are the mirror images of those shown in the drawings, the design being symmetrical with respect to a longitudinal front-to-rear center plane.
